UNITED STATES PATENT OFFICE.

JOHN T. HUGHES, OF COUNCIL BLUFFS, IOWA.

AEROPLANE SHOCK-ABSORBER.

1,378,234.

Specification of Letters Patent. Patented May 17, 1921.

Application filed August 12, 1920. Serial No. 403,003.

To all whom it may concern:

Be it known that I, JOHN T. HUGHES, a citizen of the United States, residing at Council Bluffs, in the county of Pottawattamie and State of Iowa, have invented certain new and useful Improvements in Aeroplane Shock-Absorbers, of which the following is a specification.

The present invention relates to aeroplanes, and more particularly to shock absorbers for the running gear of aeroplanes or the like machines.

An object of the invention is to provide an improved shock absorbing mechanism which will cushion the front wheels of the aeroplane in landing and will thus compensate for inequalities in the ground over which the aeroplane may be traveling at the time of alighting to the end that breakage of the wheels or parts of the aeroplane may be avoided.

A further object of the invention consists in providing a device of the above character which will have the further effect to cushion the landing device against lateral strains which are often encountered in alighting by reason of the lateral tilt of the plane or the unequal character of the landing ground.

A still further object of the invention lies in providing a simple and inexpensive construction of shock absorbing device which can be mounted on existing types of aeroplane running gear without alteration in the construction thereof and which will form a compact device presenting a neat appearance.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side view of an aeroplane having a running gear embodying a shock absorbing device constructed according to the present invention.

Fig. 2 is a fragmentary front elevational view with parts broken away of one of the landing wheels showing the invention applied thereto.

Fig. 3 is a similar view with parts shown in section.

Fig. 4 is a sectional view taken on the line 4—4 in Fig. 2.

Fig. 5 is a view in elevation with parts broken away of a detail.

Referring more particularly to the drawings, 10 designates generally an aeroplane of any conventional construction and embodying the supporting legs 11 and 12 which are united at their lower ends in the usual V-formation. According to the invention 60 the lower portion of the legs 11 are provided with vertically elongated slots 13 in which the parts of the axle 14 carrying the usual landing wheels 15 are mounted to move back and forth, but which normally occupy a position at the base of the slots by the action 70 of spring means hereinafter referred to.

The lower slotted portions of the legs 11 as well as the adjacent parts of the diagonal legs 12 which join therewith are bifurcated, 75 as clearly shown in Figs. 2 and 3, and across these bifurcated ends extend bolts 16 and 17 which, in addition to other functions presently described, also serve to brace the same.

The upper bolt 16 carries a block of rubber or other suitable material 18 constituting a bumper which at its lower end overlaps the upper end of the slotted portion 13 and is adapted to encounter the shaft 14 when it rises to the upper ends of the slots. 85

The lower bolt 17 is adapted to receive the forward rolled-over edge of a flat spring 19, while the axle 14, itself, receives a similarly rolled-over edge at the forward part of a second flat spring 20. The latter spring 90 extends at an inclination rearwardly so as to join with the substantially horizontally extending spring 19 near the lower end thereof where such springs are secured together as by bolts 21.

The bolts also serve to secure to the springs a shackle 22, the major portion of which extends vertically and is slotted, as indicated at 23, to receive the lower end of a leather or other flexible strap 24 extending 100 in looped formation. A second shackle 25 receives the upper bight of the strap 24, this last-mentioned shackle being pivoted as indicated at 26 on the leg 12.

The bifurcated portions of the legs 11 105 and 12 at opposite sides of the machine are fitted with their slotted portions 13 set inwardly a distance from the landing wheels 15 and coil springs 27 and 28 are wound in a suitable number of convolutions about the 110

axle 14 at opposite sides of such leg portions, the springs bearing at their adjacent ends against these leg portions, as clearly seen in Figs. 2 and 3.

- 5 At its outer end the spring 27 bears against a collar 29 also fitted over the shaft and carrying a set screw 30 by which it may be fixed in position thereon. The collar 29, after being adjusted axially on 10 the shaft or axle to place the spring 27 in a desired condition of tension, may be held at the new position to which it is moved by tightening the set screw 30, which must, of course, be previously loosened to permit 15 the movement of the collar just referred to. In like manner a set collar 31 is associated with the inner end of the other spring 28 and acts in a similar manner to adjust the tension of the spring.
- 20 In operation, as the plane 10 lands upon the ground the wheels 15 will first come in contact with the surface, and it is very difficult, unless the surface is exceedingly smooth and the aviator careful and skilful, 25 to avoid at least some slight jarring of the running gear. Where the ground is rough or uneven great shocks will be encountered in the landing. When the wheels 15 meet with inequalities or obstructions in the 30 surface or are caused to impinge with force against the ground, the axle 14 will be permitted to ride upwardly in the slotted portions 13 of the supporting legs in a resilient manner by the yielding of the springs 19 35 and 20 which will be pried apart by this action, and which will, of course, immediately tend to restore the axle 14 to its lowermost position in the slots 13 whenever the force of such shocks subsides.
- 40 Should the axle 14 rise to the top of the slots 13 which are made elongated to meet generally all purposes, such axle will encounter the bumper 18 which will act as a cushion stop and thereby prevent a too 45 great expansion of the springs 19 and 20 which would cause them to break.

In case the plane is at an inclination laterally when it lands or the character of the ground is such as to cause lateral strains to 50 be transmitted to the wheels 15, the body of the aeroplane will be permitted to partake of a sidewise movement with respect to the axle 14 in which it will be resisted only by the springs 27 or 28 according to

the direction of the force. A compression 55 of one or the other of these springs will be caused resulting in the yielding arrest of the lateral movement of the plane, and a subsequent restoration of the same to the initial position.

I do not wish to be restricted to the size, form, and proportions of the various parts, and obviously changes could be made in the construction herein described without departing from the spirit of the invention, it 60 65 being only necessary that such changes fall within the scope of the appended claims.

What is claimed is:

1. In combination with an aeroplane, supporting legs therefor having slots therein, 70 an axle movable in said slots, wheels on said axle, pairs of leaf springs connected together at one end and having their opposite free ends secured respectively to said axle and to said legs, means to secure the 75 joined ends of said springs to the legs, and a bumper for limiting the movement of said axle.

2. In combination with an aeroplane, a running gear therefor, an axle vertically 80 shiftable in said running gear, landing wheels on the axle, pairs of leaf springs connected together at one end and having their opposite free ends secured respectively 85 to said axle and to a fixed part of the running gear, and means to secure the joined ends of said springs to the running gear.

3. In combination with an aeroplane, bifurcated supporting legs therefor having vertically elongated slots therein, an axle 90 movable in said slots, wheels on said axle, a bumper held between the bifurcated portions of the legs and projecting downwardly into the upper portions of the slots, pairs of leaf springs connected together at one 95 end and having their opposite free ends entering between the bifurcations of the legs and being secured respectively to the axle and to said legs, and means to flexibly secure the joined ends of said springs to the 100 legs.

In testimony whereof, I have affixed my signature in presence of two witnesses.

JOHN T. HUGHES.
